UNITED STATES PATENT OFFICE.

RUDOLF HASE, OF BERLIN, GERMANY, ASSIGNOR, BY MESNE ASSIGNMENTS, TO NAMLOOZE VENNOOTSCHAP FINANZIEELE MATTSCHEPIJ "DRIEBERGEN," OF AMSTERDAM, NETHERLANDS, A COMPANY OF NETHERLANDS.

RECORDING PHONOGRAPH.

Application filed February 18, 1921. Serial No. 446,202.

To all whom it may concern:

Be it known that I, RUDOLF HASE, a citizen of the German Republic, chief engineer, residing at Friedrichstrasse 24, Berlin, 5 S.W. 48, Germany, have invented new and useful Improvements in Recording Phonographs (on which application has been made for Letters Patent in Germany No. T. 23,608 IX/42g, filed 6th February, 1920; 10 Switzerland, Nov. 15th, 1920; Austria, November 16th, 1920; Czecho-Slovakian Republic, Nov. 19th, 1920; Hungary, November 19th, 1920; Poland, November 23d, 1920; Netherlands, November 25th, 1920; 15 Finland, November 30th, 1920; France, December 1st, 1920; Belgium, December 3d, 1920; Sweden, December 4th, 1920; Great Britain, December 21st, 1920), of which the following is a specification.

20 The invention relates to phonographic apparatus, in which speech is recorded by the aid of an electromagnetic sound-box, and its purpose is to record speech automatically without the immediate co-operation, and 25 even if desired without the knowledge, of the speaker. For this purpose according to the invention the electromagnet of the sound box is connected with a sensitive microphone adapted to pick up sound waves arising in its neighborhood, and automatically to transmit corresponding current-oscillations to the recording sound-box. The use of a phonographic recorder in combination with such a sensitive microphone for purposes of dictation offers the advantage that the dictation is completely unrestrained, since the speaker's thoughts are not diverted by the necessity of speaking into the mouthpiece of an ordinary microphone or of a speaking-tube, 30 but he can speak quite naturally without reference to the apparatus, as if dictating to a shorthand-typist. As is described in more detail below by the use of a sensitive microphone (herein called a listening microphone) as the sound-receiver for the recording apparatus, conversations even between several parties can be recorded without any restraint upon the speakers. The driving mechanism may be put in action by an electromagnetically released time-lag device, so 35 that the circuit which causes the apparatus to start need only be closed momentarily, which can be done without attracting attention. Finally recording may be made com-

pletely automatic by providing in the circuit of the listening microphone a switch device actuated by the speaking current, and controlling the time-lag device, so that the apparatus works so long as speech continues.

55 In the drawings two forms of construction according to the invention are illustrated diagrammatically; Figure 1 being the simple construction in which the driving mechanism is set going by hand, while in Figure 2 is shown the device for automatic actuation.

60 The record surface is a cylinder 1, with which a recording sound-box 2 is associated in known manner. For the sake of simplicity the remaining parts of the apparatus, which are unaffected by the present invention, are not illustrated. The driving mechanism 3 is indicated as an electric motor, but 65 may be any electrically controlled motor as an electrically released clock-work. 4 indicates the listening microphone which may be of any desired construction; by way of example it is assumed to be divided into several cells indicated by the small circles 5. It is connected with the electromagnet 8 of the sound-box 2 by leads 6, 7 extending to the recording apparatus; a battery 9 is included in the circuit to supply the microphone 4. The circuit of the motor 3 can be 70 closed by a switch 10 located in the neighborhood of the listening microphone 4. The microphone will generally be inconspicuously arranged, but in as favourable a position as possible for the sound waves to impinge on it; while the switch 10 may be so placed that it can be used by the possessor of the device unnoticed by a visitor whose conversation is to be recorded. There may 75 also be associated with the switch 10 a contact in the microphone circuit, so that current is taken from the battery 9 only while the recorder is working. When conversation is to be recorded the switch 10 is closed, 80 whereupon the motor 3 starts up and sets the cylinder 1 and the traversing mechanism of the sound-box 2 in movement. The sound waves arising from the conversation 85 impinge upon the microphone cells 5, and the conversation is recorded.

90 It is desirable to put the motor 3 in circuit, not immediately by the switch 10, but through an electromagnetically actuated

time-lag device 11 (Fig. 2). The advantage of this is that the switch 10 need not be closed continuously, and the record of the conversation can be broken off without of necessity attracting the visitor's attention by manipulation, which cannot wholly be concealed, for putting the apparatus out of action. The time-lag device 11 includes an electromagnet 12 which operates the switch 10 13 of the motor 3. The switch 13 is equipped with a retarding device 14, the effect of which is that the switch only opens and disconnects the motor a certain interval of time after current is cut off from the electromagnet 12. The electromagnet 12 can be supplied from the battery 9. To put the driving mechanism 3 in action the switch 10 is momentarily closed so that the winding 12 is excited, attracts its armature and 20 closes switch 13. The motor 3 then runs so long as the retarding device holds the switch 13 closed.

In Figure 2 there is also provided a so-called phonic relay 15, which is actuated by the electrical current oscillations due to speech; this is inserted in the circuit of the time-lag device 11. This relay comprises, for instance, an electromagnet 16 which may be in series or in parallel with the electromagnet 8 of the sound-box 2; and a contact adapted to be closed by vibration, preferably a microphone 17, which is in the circuit of the electromagnet 12 of the time-lag device 11.

The operation of this construction is as follows:—If sound waves strike the listening microphone 4 the electromagnet 16 of the phonic relay 15 is excited. This so far diminishes the resistance of the microphone contact 17 that the electromagnet 12 responds and the switch 13 for the motor 3 is closed. The cylinder 1 then begins to rotate, and the conversation is recorded in the usual way. It might happen that the cylinder 1 had not attained a sufficient speed at the beginning of the conversation, so that the beginning of the record was mutilated; it is therefore desirable to provide in parallel with the microphone contact 17 a switch 10 which can be inconspicuously and momentarily closed before conversation begins, so that the cylinder attains a sufficient speed to record the first words clearly. So long then as sound waves strike

the listening microphone 4 the electromagnet 12 of the time-lag device 11 remains excited, and by it the switch 13 is held closed. The circuit also remains closed during pauses in the conversation, because the retarding device 14 prevents immediate opening of the contact 13. Only if current oscillations cease for some time does interruption occur, so that the cylinder 1 does not run uselessly.

The phonic relay 15 with the microphone device 17 above described is an example only of a switch device set in action by electrical oscillations.

What I claim is:

1. A sound recording apparatus comprising in combination a record surface, a motor driving said surface, electrical means including a switch for putting said motor into and out of action, means for delaying the opening of said switch, an electromagnet closing said switch, a source of power connected with said electromagnet, a hand operated switch in the circuit of said electromagnet, a contact in parallel with said hand operated switch adapted to be closed by sound vibration, and means for receiving sounds and recording them upon said record surface.

2. A sound recording apparatus comprising in combination a record surface, a motor driving said surface, electrical means including a switch for putting said motor into and out of action, means for delaying the opening of said switch, an electromagnet closing said switch, a source of power connected with said electromagnet, a hand operated switch in the circuit of said electromagnet, a microphone in parallel with said hand operated switch, an electromagnetic sound box associated with said record surface to inscribe a record therein, a second sensitive microphone separate from but connected with said electromagnetic sound box through said source of power, and a receiver mechanically connected with said first microphone and electrically connected with said second sensitive microphone.

In testimony whereof I have signed my name to this specification.

RUDOLF HASE.
